UNITED STATES PATENT OFFICE.

FRANK S. INGOLDSBY, OF PINE LAKE, MICHIGAN, ASSIGNOR TO THE INGOLDSBY AUTOMATIC CAR COMPANY, OF CLEVELAND, OHIO, A CORPORATION OF WEST VIRGINIA.

DUMP-CAR.

1,344,403.

Specification of Letters Patent. Patented June 22, 1920.

Application filed October 16, 1916. Serial No. 125,787.

To all whom it may concern:

Be it known that I, FRANK S. INGOLDSBY, a citizen of the United States, residing at Pine Lake, in the county of Oakland and State of Michigan, have invented a certain new and useful Improvement in Dump Cars, of which the following is a full, clear, and exact description, reference being had to the accompanying drawings.

10 My prior Patent, No. 1,013,552, issued January 2, 1912, shows and claims a combined locking and raising mechanism for dump cars, so arranged that oscillations of a lever, which in final position locks the doors, may serve to raise them. The invention is there shown as embodied in a car of the Ingoldsby type, wherein a load-supporting door has projecting floor beams which may be engaged by hooks on the 15 sides of the car to hold it in closed position, the hooks on the two sides being operated by two levers respectively. To raise the doors, a longitudinal bodily-movable bar is provided on each side, which is connected by flexible members with the door and has teeth which may be engaged by a pawl carried by an extension of the main locking lever. A suitable detent pawl is also provided, which may engage these 20 teeth. Thus oscillations of the main lever may serve to gradually move the longitudinal bar and pull up on the chains to close the door.

The present invention is in the nature of an improvement on the structure shown in the prior patent referred to, and includes means for preventing undue slack in the chains attached to the doors; means for effectively guiding the chains; means preventing any rebound of the longitudinal bar; means for giving the detent pawl a spring engagement with the teeth on the bar, when desired, while enabling it to be idle when the car is ready for discharge; 40 means for insuring the release of the detent pawl and the ratchet pawl when the car is locked; and, finally, means for protecting the teeth and preventing them from being stripped when the car is being unloaded. All these features will be herein-after more fully explained and their essential characteristics summarized in the claims.

In the drawings, Figure 1 is a side elevation of a portion of a car embodying my

invention; Fig. 2 is a transverse section of 55 the same, on a larger scale; Fig. 3 is an end view of a portion of the car adjacent to the right-hand side; Fig. 4 is a fragmentary plan adjacent to the end of the car showing the detent pawl and its immediately coacting parts; Fig. 5 is a detail in cross section showing the guiding pulley carried by the lower chord; Fig. 6 is a detail in longitudinal section illustrating the bodily movable operating bar and chain and the two pulleys which coact with the bodily-movable bar and support and guide the chain; Figs. 7 to 10 inclusive show a different arrangement of locking device for the detent pawl; Fig. 7 is a partial side 70 elevation of a car equipped with a locking device for the main operating lever, the locking device being connected with the detent pawl; Fig. 8 is an end view (partly broken away and partly sectioned) of a 75 portion of the car shown in Fig. 7; Fig. 9 is a detail in cross section on the line 9—9 of Fig. 7, looking upwardly; Fig. 10 is a fragmentary elevation looking in the opposite direction from Fig. 7, on a larger 80 scale and showing in full lines the lever-locking device in locked position; Fig. 11 is a detail on the line 11—11 of Fig. 7; and Fig. 12 is a detail illustrating the construction of the longitudinal bar and the connection of the chain thereto.

Referring to the parts by numerals, 15 represents the side of a car which is shown as a plate-girder having a lower chord 16, an upper chord 17, and side stiffeners 19. 90 20 designates a central longitudinal ridge member which may be employed. 22 indicates inclined end floors. Such construction may readily divide the car into two hopper portions, each of which may be 95 closed by a door. However, the arrangement of the interior of the car, the number of doors, and the position or direction of the axes on which they swing, may be varied as desired.

100 As shown in the drawings, the dumping doors are hinged on longitudinal axes at the lower edges of the center ridge 20. These doors are designated 25. Their hinge pivots are shown at 26. The doors are provided 105 with several floor beams 27, extending across them and projecting beyond them.

Pivoted to the sides of the car are hooks

or levers 30 the lower ends of which are adapted to engage beneath the projecting ends of the floor beams 27. Each of these hinged levers is pivoted near its lower end as 5 illustrated at 31. The hook portion may conveniently be beveled at its engaging edge 32, and the projecting ends of the floor beams may be hooked in a plane parallel with the door, as illustrated at 33, so that the 10 side hooks and the floor beam hooks interlock with each other and serve to pull the doors snugly up against the lower chord 16 and at the same time hold the side of the car against outward bulging.

15 To hold the hooking levers 30 in their locked position, as well as to release them as a unit, they are all pivoted at their upper ends to a longitudinal link 35 which is connected at its end to the main operating lever 20 40. This lever is shown as pivoted at 41 to the side of the car, which is suitably reinforced at this point. The movement of the lever 40 is limited by the guide iron 45, shown as extending alongside of the path of 25 movement of the lever and secured at one end to the car side and at the other to an inclined end strut 47.

It will be seen from the construction described, that when the lever is in the position shown in Fig. 1 the hooks engage beneath the floor beams and support the doors. If, however, the lever be thrown forward (*i. e.*, toward the right, Fig. 1), the lever hooks will be withdrawn from the floor beams and 30 35 the door will drop by gravity.

To raise the door or doors, I provide the bodily-movable longitudinal bar 50, to which are anchored chains 51, of which there may be any desired number and which extend 40 over pulleys 52 and thence downwardly and are secured at their lower ends to the doors; for example, to the projecting ends of floor beams 27 on the under sides of the doors or to separate attachments 28 fastened to the 45 door. Coacting with the pulleys 52, over which the chains pass, are guide pulleys 54. Where the chain passes across the lower chord of the car I provide a suitable guide, which may be a pulley consisting of a sleeve 50 55 journaled on the intermediate portion of a U-bolt 56, the legs of which extend upwardly through the outstanding flange of the lower chord and are bolted to it. One or both of the pulleys 52 and 54 which support and 55 guide the chain also support and guide the longitudinal bar 50. To effect this these pulleys may be provided with flanges 53 at their edges. The end portion of the bar 50 is shown as supported by flanged pulleys 57. 60 The longitudinal bar lies close to the car side and extends through openings in the stiffeners, which effectively prevent any displacement of the bar.

It will be seen that a movement of the bar 65 50 toward the left in Fig. 1, will result in

drawing upwardly the depending portions of the chains and thus raising the doors. To cause this movement of the bar I provide ratchet teeth 60, on its upper face, with which may coact a pawl 61, pivoted at 62 to 70 a lower extension of the main operating lever 40. I provide also a detent pawl 64 which extends transversely of the end of the car and is intermediately pivoted at 65 and stands above the teeth 60 and below an extension or tail 66 on the pawl 61.

When the outer end of the detent pawl 64 is in elevated position, as shown in Fig. 1, it is idle, and it also holds in idle position the feeding or ratchet pawl 61. Therefore, in 80 this position the lever is ready to release the supporting hooks as usual. To enable the pawls, however, to effect the movement of the bar 50, the outer end of the pawl 64 is lowered to engage the teeth 60, and this releases the feeding pawl 61 so that it may also engage these teeth. Then, an inward shoving on the upper end of the lever 40 causes an outward movement of the bar 50. The gain made is held by the detent pawl 64, 90 while the following outward movement of the lever 40 carries the pawl 61 inward to obtain a new hold on the operating bar 50 and force it endwise on the next stroke of the lever 40.

95 In order to retain the operating bar 50 normally in its left-hand position (Fig. 1), when the pawls are released from it, and thus take up the slack on the chains, I prefer to mount this bar in a position inclined 100 downwardly toward the operating end of the car, as shown in Fig. 1. A slight incline in this direction is sufficient to insure the bar remaining in the position shown or to cause it to gravitate into such position if displaced. 105 The bar may conveniently consist of two parallel straps rigidly secured together a suitable distance apart to receive the end link of the chain 51, as shown in Fig. 6. 58 designates rivets connecting the bars, and 110 59 distance sleeves, through which some of these rivets pass. The teeth 60 may be provided on a T-shaped block 63 secured in the upwardly opening slot between the strips of the bar and held by rivets.

115 When the load is dumped by releasing the doors, the bar 50 is moved rapidly to the right, as the doors drop. Should the upper ends of the chains pass beyond the pulleys 52, they then ride over pulleys 54; but momentum will not carry the bar far beyond the normal open position, for as soon as the bar begins to pull the chains in the other direction the momentum is counteracted by the weight of the door, which the chains 120 would have to raise. The incline of the bar also gives a gravity factor opposing this movement by momentum.

125 It will be seen from the above description that by the simple expedient of inclining 130

the bar 50 I am able to prevent its displacement and to keep the chains from sagging, and by the use of the double pulleys 52, 54, I can effectively take care of the inertia of the bar when the doors are dropped. The guides 55 protect the lower chord and prevent injury to the chain. The whole, therefore, makes a simple and efficient construction to meet the conditions resulting from the quick discharge of a heavy load. The toothed portion of the raising bar may, if desired, be protected by a suitable housing; for example, the Z-bar 69, secured to the side of the end platform and overhanging the bar 50, as shown in Figs. 1, 7 and 11. This not only acts as a housing to protect the toothed portion of the bar, but also acts as a guide to prevent any undue upward movement of the bar and consequent stripping of the teeth by contact with the pawls when the car is being unloaded.

As stated, the doors are rapidly raised by simply oscillating the main operating lever 40, the pawl 64 holding the gain made by the pawl 61. In some installations it is sufficient for the operator to maintain the pawl 64 active by holding his foot on the outer end thereof and pressing it downward or under the inner end and pressing it upward against the action of gravity on the longer inner end 68. For some purposes, however, it is desirable to have the pawl 64 pressed by a spring into engagement with the teeth 60. For such installations I may provide the spring 70 shown in Figs. 3 and 4. This spring is a leaf spring pivoted on a vertical pivot by the pin 71 to a bracket 72 secured to the car. In normal running the spring is idle, being in the position shown by dotted lines in Figs. 3 and 4, and out of contact with the pawl 64. The spring may be retained against accidental displacement from this position by lugs 73 on the bracket engaging the edges of the spring. When, however, it is desired to use the spring it is sprung across one of these lugs and thus occupies a position longitudinal of the car, where it stands between the lugs 74, and extends beneath the pawl 64, as shown in Fig. 4. This will give a spring action to the pawl, so that the ratchet teeth 60 may readily slide beneath it in moving toward the left, but the pawl will effectively hold the gain made by engaging that face of the ratchet which is at right angles to the bar. The spring is retained in this position until the door is raised.

Following the last raising stroke of the operating lever 40, which is a forward shoving of the upper end, the lever is returned to the position shown in Fig. 1. This is idle as far as the raising by the chains is concerned, but it brings the hooked ends 32 beneath the floor beams 33 and locks the doors in final position. After the doors are

locked, the spring 70 is returned, manually, or by the operator's foot, from beneath the pawl arm 68, and this pawl is thus released by gravity from the operating bar 50. As the inner end 68 of the pawl 64 drops by gravity, its outer end raises the tail 66 of the feeding pawl 61, so that both these pawls come into idle position, as shown in Fig. 1.

In some cases it is desirable to provide means for insuring against the operator forgetting to release the detent pawl before he releases the load, since to release the load with the detent pawl in engagement would throw greater strain on the raising mechanism than it is intended to take. To provide for this I may arrange an automatic release of the pawls. It is customary to provide Ingoldsby cars with a locking dog which may lock the main operating lever 40 against movement, this locking dog being turned to active position as soon as the doors are raised and locked. By suitably connecting this locking dog with the detent pawl 64 I can insure that pawl and the feeding pawl being thrown into idle position as soon as the locking dog is moved into active position.

A construction illustrating the operation just mentioned is shown in Figs. 7 to 10 inclusive. In these figures 80 indicates a bifurcated bracket mounted on the inclined strut 47 and carrying a dog 81, pivoted between the standards of the bracket, and adapted to be turned in front of the operating lever 40 and thus prevent the movement of that lever. This dog is shown as an L-shaped bar pivoted adjacent to its angle at 83. The higher standard 82 of the bracket has a hole which may align with a corresponding hole 84 in the extension 85 of the dog when the dog is in locking position. When these holes are aligned the dog may be prevented from accidental or intentional displacement by inserting a locking pin or padlock hasp 110 through such aligned holes.

Now to enable this locking dog to automatically release the detent pawl, I may provide the mechanism shown in Fig. 8 where a lever 87 is intermediately pivoted at the end of the car and has its inner end connected by a tension spring 88 with the inner extension 68 of the pawl 64. The other end of the lever 87 lies alongside of the end of the car side. When the inner end of the lever 87 is pulled upwardly by hand, it raises the inner end of the detent pawl and puts the spring 88 under tension. To hold the lever 87 in this position its outer end passes beneath a catch 90, which is pivoted to a bracket 91 secured to the inclined strut 47. I connect this catch by a chain 93 to the arm 85 of the locking dog.

The result of the construction described is that when this dog is turned to active position

sition, to lock the lever at the end of the raising operation, shown in full lines in Figs. 8-10, the pull on the chain 93 swings the catch 90 to release the lever 87. This lever and the detent pawl accordingly drop by gravity into the position shown in full lines in Fig. 8, thus entirely releasing the raising bar. Before the load can be dumped, however, the locking dog 81 must be turned back away from the lever 40, into the position shown in broken lines in Fig. 8. In doing this, the catch 90 drops into active position (shown in broken lines in Fig. 10), so that as soon as the load has been dumped it is possible to swing the lever 87 on its pivot and latch its outer end beneath the catch, thus putting the detent pawl in active position and holding it there under spring tension. This same movement releases the pawl 61 so that the mechanism is in position for action to engage and draw back on the bar 50, which by the dropping of the load has been carried to the right.

It will be seen from the above that as soon as the oscillations of the operating lever 40 have raised the doors, and they are locked by the final backward movement of the lever 40, this lever may then be itself locked by positioning the locking dog illustrated in Figs. 7 to 10, this positioning, as explained, insuring the release of both the detent pawl and the feeding pawl.

Having thus described my invention what I claim is:

1. In a dump car, the combination, with a dumping door, of a closing device comprising an inclined bodily-movable bar, a flexible member leading from the bar over a pulley to the door, and means for moving the bar longitudinally thereof, the incline of the bar being in the direction to give it a gravitational tendency to take up the slack in the flexible member.

2. In a dump car, the combination, with a dumping door, of a closing device comprising an inclined bodily-movable bar resting on pulleys at the side of the car, a connection from the bar to the door, and means for moving the bar, the incline of the bar being in the direction to give it a gravitational tendency to stay in the closed position.

3. In a dump car, the combination with a door, of a bar, a flexible member connected to the bar and leading over one or more pulleys to the door, teeth on the bar, and a lever and pawl arrangement coacting with the teeth to shove the bar longitudinally, said bar inclining downwardly toward the lever and pawl mechanism.

4. In a dump car, the combination with a door, of a bodily-movable bar, a flexible member connected with the bar passing over a pulley to the door, and an adjacent pulley coacting with the flexible member and

adapted to support the same if the bar overruns the normal open position.

5. In a dump car, the combination with a door, of a bodily-movable bar, a flexible member connected with the bar and the door, and a pair of adjacent pulleys with the flexible member running between them, at least one of said pulleys being adapted to support the bar.

6. In a dump car, the combination of a dumping door, a flexible member connected therewith, a pair of pulleys carried at the side of a car between which said flexible member runs, an operating bar extending along the side of the car and riding on at least one of said pulleys, said flexible member being connected to the operating bar, and means for moving the bar longitudinally.

7. In a dump car, the combination with a dumping door, of a flexible member connected therewith, two pulleys side by side between which the flexible member runs, said pulleys being provided with flanges, a bar riding on at least one of said pulleys, the flexible member being anchored to the bar, and means for moving the bar longitudinally to raise the door.

8. In a dump car, the combination with a car side having a lower chord with an outstanding flange, of a longitudinal bar above said chord, a guide pulley above the chord, and a flexible member connected with the bar passing across the pulley and through an opening in the flange and secured at its lower end to the door, and a guide carried by the outstanding flange of the lower chord in a position for the flexible member to engage it.

9. In a dump car, the combination of a car side having a lower chord with an outstanding flange, a dumping door, a longitudinally movable bar at the side of the car, a pulley at the side of the car, a flexible member connected to the longitudinal bar and passing across the pulley and leading downwardly to the door, and a guide pulley mounted on a longitudinal axis at the lower edge of the car, said guide pulley comprising a roller journaled on the intermediate portion of a U-bolt, the arms of which extend through the outstanding member of the lower chord of the car.

10. In a dump car, the combination with a dumping door of a bodily movable bar, a flexible member connected to the bar and passing over a pulley and thence to the door, an operating pawl adapted to engage teeth on the bar for moving the bar, and a stationary plate located beyond the point of engagement of the pawl and extending lengthwise of the bar and secured at its inner edge to the car, the plate thence projecting outwardly above the bar and having a downward flange at its outer edge.

whereby a protection supported by the side only is provided above the bar.

11. In a dump car, the combination, with a dumping door, of a bodily-movable bar 5 and mechanism connecting it with the door, whereby the movement of the bar may close the door, said bar having teeth, a movable pawl to engage said teeth, and a plate Z shaped in cross section having an upward 10 flange secured to a longitudinal side portion of the car, an intermediate web lying over the bodily movable bar and a downward flange on the outer side of the bodily movable bar.

12. In a dump car, the combination, with a dumping door, of a bodily-movable bar, a connection between the bar and the door, said bar having teeth, a lever, a pawl operated by said lever adapted to engage said 20 teeth, a detent pawl adapted to engage said teeth, and a flanged plate secured by one flange to the end portion of the car and extending over the end portion of the bar beyond the pawls mentioned.

13. In a dump car, the combination with a dumping door, of a closing device comprising a bodily-movable bar and a connection between the same and the door, said bar having an upwardly opening slot in it and a 30 T-shaped block having teeth on its upper face and having its shank standing in said slot, and mechanism to engage said teeth to operate the bar to close the door.

14. In a dump car, the combination with a dumping door, of a closing device comprising a bodily-movable bar, made of two parallel spaced strips connected together, a pulley, and a flexible member extending across the pulley and anchored at one end 40 to the door and at the other to the bar between its side strips, a T-shaped block having teeth on its upper face and having its shank standing between said strips and secured to them, and mechanism to engage 45 said teeth to operate the bar to close the door.

15. In a dump car, the combination with a dumping door, of a bodily-movable bar, a flexible member connected to the bar and 50 passing over a pulley to the door, an operating pawl adapted to engage teeth on the bar for moving it, a detent pawl to hold the gain so made, a spring adapted to press the detent pawl toward the bar, and means 55 for rendering the spring idle when desired.

16. In a dump car, the combination of raising mechanism including a longitudinal bar, an operating pawl and a detent pawl therefor, a lever, a spring connecting said 60 lever with the detent pawl, and means for latching said lever.

17. The combination, in a dump car, of a dumping door, raising mechanism therefor including a movable bar having teeth, 65 an operating pawl therefor, a detent pawl,

mechanism for locking the car, and mechanism operated automatically thereby for releasing one of said pawls.

18. The combination, in a dump car, of a dumping door, raising mechanism therefor 70 including a movable bar having teeth, an operating pawl therefor, a detent pawl adapted when thrown out to throw out the operating pawl, mechanism for locking the car, and mechanism operated automatically 75 thereby for releasing said detent pawl.

19. In a dump car, the combination of raising mechanism including a longitudinal bar, an operating and a detent pawl therefor, a spring device for elastically pressing 80 the detent pawl toward the bar, and automatic means for releasing the spring device.

20. In a dump car, the combination with a dumping door, of a closing device therefor, a device for locking the same closed, 85 and means for releasing the closing device consequent upon the effective locking of the door.

21. In a dump car, the combination, with a dumping door, of closing mechanism 90 therefor, a system of hooks and a lever connected therewith for holding the door closed, a locking device for said lever, and means whereby the operation of said locking device may release the closing mechanism. 95

22. In a dump car, the combination, with a dumping door, of a system of hooks and a lever connected therewith for holding the door closed, a locking device for said lever, 100 a closing mechanism comprising a longitudinal bar and a flexible member leading therefrom over a pulley to the door, and means whereby the operation of said locking device may release the closing mechanism. 105

23. The combination, in a dump car, of a dumping door, raising mechanism therefor including a movable bar having teeth, an operating pawl therefor, a detent pawl, a 110 mechanism for holding the door closed including an operating lever, a locking dog for said lever, and releasing means for one of said pawls operated by said dog.

24. The combination, in a dump car, of a dumping door, raising mechanism therefor including a movable bar having teeth, an operating pawl therefor, a detent pawl, locking hooks for the car, a main locking lever connected with said hooks and also with 115 said operating pawl, a locking dog for said lever, and releasing means for said pawls operated by said dog.

25. In a dump car, the combination, with a dumping door, of raising mechanism 120 therefor having a pawl, mechanism for holding the door closed, a locking dog for said mechanism, a spring for the pawl, and a connection between said spring and locking dog. 125

26. In a dump car, the combination of a dumping door, hooks on the side of a car adapted to support the door, a main lever connected with the hooks, raising mechanism for the door including a movable bar connected with the door, a feeding pawl therefor connected with the main lever, and a detent pawl, a lock for the main lever, and a releasing connection between said lock and one of the pawls mentioned.

27. In a dump car, the combination of a dumping door, hooks on the side of a car adapted to support the door, a main lever connected with the hooks, a movable bar, a pulley a flexible connection anchored to the bar and the door and passing across the

pulley, a feeding pawl for the bar connected with the main lever, a detent pawl adapted when thrown out to throw out the feeding pawl, a lock for the main lever, and a releasing connection between said lock and said detent.

28. In a dump car, the combination, with the car body and dumping door, of a movable bar, a chain connecting it with the dumping door, said bar being composed of two parallel strips, distance tubes between them, and through-rivets extending through the strips and the distance tubes.

In testimony whereof I hereunto affix my signature.

FRANK S. INGOLDSBY.
